US0D1061088S

(12) **United States Design Patent** (10) **Patent No.:** **US D1,061,088 S**
(45) **Date of Patent:** **** Feb. 11, 2025**

(54) **SHOULDER PILLOW**

(71) Applicant: **Justin Adelipour**, New York, NY (US)

(72) Inventors: **Justin Adelipour**, New York, NY (US);
Catalina Navarro, Aurora (CA); **Lara**
Clair, Stouffville (CA); **Bartek**
Zalewski, Richmond Hill (CA)

(73) Assignee: **Justin Adelipour**, New York, NY (US)

(**) Term: **15 Years**

(21) Appl. No.: **29/824,890**

(22) Filed: **Jan. 27, 2022**

(51) LOC (15) Cl. **06-09**

(52) U.S. Cl.
USPC **D6/601**

(58) **Field of Classification Search**

USPC D2/861; D6/596, 597, 601, 604, 716.5;
D24/190, 191
CPC A47G 9/00; A47G 9/10; A47G 9/1009;
A47G 9/1027; A47G 9/1054; A47G
9/1072; A47G 9/1081; A47G 9/109;
A47G 2009/1018

See application file for complete search history.
